MAGNETIC TAPE TRANSPORT

Albert W. Martin, Santa Clara, Calif., assignor to Ampex Corporation, Redwood City, Calif.

Filed Oct. 16, 1970, Ser. No. 25,533

Term of patent 14 years

Int. Cl. D14—02

U.S. Cl. D26—5

FIG. 1

FIG. 2

FIG. 3

FIG. 1 is a front, top and left side perspective view of a magnetic tape transport showing my new design, the bottom being conventionally plain;

FIG. 2 is a front, top and right side perspective view of the transport of FIG. 1, with the cover door in an opened position; and

FIG. 3 is a rear elevation view of the transport of FIGS. 1 and 2.

I claim:

The ornamental design for a magnetic tape transport, substantially as shown and described.
